UNITED STATES PATENT OFFICE.

WILLIAM S. REED, OF TURTLE CREEK, PENNSYLVANIA, ASSIGNOR OF FIVE-EIGHTHS TO JOHN D. FRY, OF PITTSBURG, PENNSYLVANIA, AND EWING MATTHEWS, OF AGNEW, PENNSYLVANIA.

WIRE-STRETCHER.

SPECIFICATION forming part of Letters Patent No. 742,903, dated November 3, 1903.

Application filed August 25, 1900. Renewed August 1, 1902. Serial No. 118,003. (No model.)

To all whom it may concern:

Be it known that I, WILLIAM S. REED, a citizen of the United States, residing at Turtlecreek, in the county of Allegheny and State 5 of Pennsylvania, have invented a certain new and useful Improvement in Wire-Stretchers, of which the following is a specification.

My invention relates to devices adapted to extend or stretch wire, as for fencing, trolley-conductors, or other purposes.

The object of my invention is to produce a simple and efficient device adapted to accomplish this object and at the same time to produce a device by the use of which the separable ends of two wires may be connected and held taut until the repair-man splices or secures the same together.

Another object of my invention is to enable a workman to progressively stretch a wire—*i.e.*, 20 to hold the wire tight and prevent it slipping back at every successive stretching thereof; and to these ends my invention consists in the novel construction and arrangement of parts hereinafter specifically described, reference 25 being had to the accompanying drawings, which form a part of this specification, and in which—

Figure 1 indicates a side elevation of my improved wire-stretcher. Fig. 2 is a plan view of the same. Fig. 3 is a section taken on the line A B of Fig. 1 looking to the left. Fig. 4 is a section taken on the line C D of Fig. 1 looking to the right. Fig. 5 is an elevation of the lever end of my apparatus. 30

Fig. 6 is a side elevation of a modified form of my apparatus. Fig. 7 is a side elevation, partly in section, showing extensibility of the shank.

Referring to said drawings, 1 is a shank or 40 bar, the ends, respectively, of which are provided with upwardly-projecting members or prongs 2 and 3, in which or between which, respectively, in direct alinement are journaled or secured the wire-grasping jaws 4 and 5.

45 The said jaws comprise two vertically-arranged segmental-shaped blocks, the grasping-faces 7 of which are serrated or corrugated and are kept normally closed by the tension of springs 8. A short distance from 50 the upwardly-projecting members or prongs

2, in which the jaws 4 are secured, a guide 9 is secured upon or made part of said bar or shank. A lever 10 is pivoted between said members or prongs 2 and guide 9, the bar having an oblong slot or opening 12, 55 substantially the width of the shank, in which the said lever is pivoted upon the short studs 13, which project from each side of said lever into the slots formed on the interior surface of side walls of said opening. The upper end 60 of said lever is bifurcated, in the members of which grasping-jaws 14 are similar to those located in the members or prongs are secured, the said jaws being retained normally closed by the tension of the spring 15. 65

In Fig. 6 I have shown the shank or bar with the guide 9 omitted, and in Fig. 7 I have shown the same to be extensible, one part being projected in a slot *a* and adapted to slide and be extended therein, a bolt or other suitable means *b* being used to securely fasten both parts when properly adjusted to the required length. On the lever end of the shank I provide an eyelet or staple 16, through which or in which a ring 17 is secured, the 75 said ring being for the purpose of slipping over the upper edge of the wire to hold the same in the jaws and prevent upward tension pulling it thereout. The opposite end of said shank may likewise be provided with a staple 18 for the purpose of hanging or securing the same to a post when used in stretching fence-wire. 80

The operation of my apparatus is as follows, to wit: In connecting the separate ends 85 of a trolley-wire the severed ends are respectively secured in the jaws 2 and 3, and said jaws being set in opposite directions tension coming from opposite points has a tendency to close both sets of jaws upon the wire in 90 their grasp. The shank being extensible enables the workmen to connect the severed ends even if the same are reasonably widely apart. In stretching wire with my apparatus the wire being, as heretofore stated, secured 95 between the jaws—*i.e.*, the retaining-jaws located in the members or prongs, also in the jaws of the lever—the lever is then drawn to the left and has a tendency to pull on the wire in the direction in which the wire is free to 100

move in said retention-jaws 4. Upon the reverse movement of the lever the lever-jaws are released on the wire, the retention-jaws then holding the same, and the movement of the lever is continued until the wire is sufficiently stretched.

What I claim as my invention, and desire to secure by Letters Patent, is—

1. A wire-stretcher comprising a bar having upwardly-projecting members in which wire-grasping jaws are mounted, in combination with a lever the upper end of which is bifurcated and has mounted therein wire-stretching jaws the said lever being pivotally connected to said bar between the upwardly-projecting members thereon the said wire-grasping jaws carried by said lever being in alinement with the wire-grasping jaws mounted in the members of the bar.

2. In a wire-stretching device, a shank having on the ends thereof upwardly-projecting members in which wire grasping and retention jaws are mounted, and a guide lo-

cated between said members, and means to prevent the wire pulling out in an upward direction of said jaws, in combination with a lever one end of which is bifurcated and provided with wire-grasping jaws mounted therein adapted to be brought into alinement with the jaws located in the members of said shank.

3. In a wire-stretching apparatus, a bar adapted to be extended or lengthened the ends of the same having upwardly-projecting members in which wire grasping and retention jaws are mounted, in combination with a lever one end of which is bifurcated and provided with wire-stretching jaws and adapted to be mounted in said shank in alinement with the jaws mounted in the members.

In testimony whereof I have hereunto set my hand in the presence of two subscribing witnesses.

WILLIAM S. REED.

In presence of—

C. A. WILLIAMS,
JAMES C. HERRON.
